(57) **CLAIM**

The ornamental design for a treadmill, as shown and described.

DESCRIPTION

FIG. 1 is a top, right-side perspective view of a treadmill showing our new design;

FIG. 2 is a bottom, right-side perspective view thereof;

FIG. 3 is a front, left-side-side perspective view thereof;

FIG. 4 is a top plan view thereof;

FIG. 5 is a bottom plan view thereof;

FIG. 6 is a left-side elevation view thereof;

FIG. 7 is a right-side elevation view thereof;

FIG. 8 is a front elevation plan view thereof;

FIG. 9 is a rear elevation view thereof;

FIG. 10 is an enlarged view of the area labeled 10 in FIG. 1 thereof; and

FIG. 11 is an enlarged view of the area labeled 11 in FIG. 2 thereof.

FIG. 12 is a top, right-side perspective view of a treadmill showing the second embodiment of our new design;

FIG. 13 is a bottom, right-side perspective view thereof;

FIG. 14 is a front, left-side-side perspective view thereof;

FIG. 15 is a top plan view thereof;

FIG. 16 is a bottom plan view thereof;

FIG. 17 is a left-side elevation view thereof;

FIG. 18 is a right-side elevation view thereof;

FIG. 19 is a front elevation view thereof;

FIG. 20 is a rear elevation view thereof;

FIG. 21 is a top, left side perspective view of an alternative state thereof;

FIG. 22 is a bottom right-side perspective view in an alternative state thereof;

FIG. 23 is a top plan view in an alternative state thereof;

FIG. 24 is a bottom plan view in an alternative state thereof;

FIG. 25 is a left-side elevation view in an alternative state thereof.

(Continued)

FIG. 26 is a right-side elevation view in an alternative state thereof;
 FIG. 27 is a front elevation view in an alternative state thereof;
 FIG. 28 is a rear elevation view in an alternative state thereof;
 FIG. 29 is an enlarged view of the area labeled 29 in FIG. 12 thereof; and
 FIG. 30 is an enlarged view of the area labeled 30 in FIG. 13 thereof.
 FIG. 31 is a top, right-side perspective view of a treadmill showing the third embodiment of our new design;
 FIG. 32 is a bottom, right-side perspective view thereof;
 FIG. 33 is a top, left-side perspective view thereof;
 FIG. 34 is a top plan view thereof;
 FIG. 35 is a bottom plan view thereof;
 FIG. 36 is a left-side elevation view thereof;
 FIG. 37 is a right-side elevation view thereof;
 FIG. 38 is a front elevation view thereof;
 FIG. 39 is a rear elevation view thereof;
 FIG. 40 is a bottom perspective view in an alternative state thereof;
 FIG. 41 is a top, right-side perspective view in an alternative state thereof;
 FIG. 42 is a top plan view in an alternative state thereof;
 FIG. 43 is a bottom plan view in an alternative state thereof;
 FIG. 44 is a left-side elevation view in an alternative state thereof;
 FIG. 45 is a right-side elevation view in an alternative state thereof;
 FIG. 46 is a front elevation view in an alternative state thereof;
 FIG. 47 is a rear elevation view in an alternative state thereof;
 FIG. 48 is an enlarged view of the area labeled 48 in FIG. 31 thereof; and,
 FIG. 49 is an enlarged view of the area labeled 49 in FIG. 32 thereof.

The broken lines in the drawings illustrate portions of the treadmill that form no part of the claimed design. The dot-dash broken lines demarcating portions of the treadmill in FIGS. 1, 2, 12, 13, 31, 32 illustrated in enlarged views in FIGS. 10, 11, 29, 30, 48, 49 form no part of the claimed design.

1 Claim, 49 Drawing Sheets
